(57) **CLAIM**

The ornamental design for a children's flotation vest with headrest, as shown and described.

DESCRIPTION

FIG. 1 is a top, front, left side perspective view of a children's flotation vest with headrest showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom, rear perspective view thereof;

FIG. 9 is an enlarged view of the portion labeled "9" in FIG. 1; and,

FIG. 10 is an enlarged view of the portion labeled "10" in FIG. 1.

The broken lines shown in the figures are for the purpose of illustrating portions of the children's flotation vest with headrest and from no part of the claimed design. The dot-dash broken line circle frames define the boundary of an enlarged view and form no part of the claimed design.

1 Claim, 10 Drawing Sheets
